UNITED STATES PATENT OFFICE.

FREDERICK N. ROSS, OF PONTIAC, MICHIGAN, ASSIGNOR TO BUTTON ATTACHING MACHINE CO., OF PONTIAC, MICHIGAN, A CORPORATION OF MICHIGAN.

BUTTON-ATTACHING MACHINE.

Application filed April 16, 1923. Serial No. 632,310.

To all whom it may concern:

Be it known that FREDERICK N. Ross, citizen of the United States, residing at Pontiac, in the county of Oakland and State 5 of Michigan, has invented certain new and useful Improvements in Button-Attaching Machines, of which the following is a specification.

This invention relates to a button attaching machine and more particularly to one which is used for attaching buttons to a fabric that may be readily removed from the fabric.

The style of buttons which this machine 10 is adapted to attach to the fabric are metal back buttons having an eye secured thereto. The said eye is adapted to be inserted through a button hole in the fabric, and the machine forms a wire loop or split ring 15 through the said eye, which will prevent the button from coming loose from the fabric. With this construction, however, one can remove the button from the fabric by forcing the wire retaining ring through 20 the button hole in a similar way that an ordinary cuff link is detached from the cuff.

The object of the present invention is to provide means whereby the operator may readily locate the button at the exact place 25 on the fabric where it is to be attached. This machine is intended to eliminate any guess work as to the location of the button on the part of the operator, and to eliminate the waste which results from the operation of 30 the present machines on the market.

A further object is to provide a positive actuation of the cut-off and ejector plunger. Furthermore, it is desired to have a machine 35 that will absolutely stop at one complete operation; i. e., the attaching of one button to the fabric, and to prevent any likelihood of the machine overrunning, which prevents any likelihood of an accident.

Another object is to provide means for 40 locating the resting position of the button, just prior to the attaching operation, at the level of the work table, so that the eye of the button may extend through the button hole of the fabric as the operator lays the 45 fabric upon the work table.

A still further object is to provide means whereby the machine may be set in an in-

operative position when a button is jammed in the plunger head or feed channel, so that the operator may easily remove the 55 jammed button with a pair of pliers or some other tool.

In the drawings:

Fig. 1 is a front elevation of the machine. Fig. 2 is a top plan view thereof. 60

Fig. 3 is a side elevation partly in section, taken on the line 3—3 of Fig. 4.

Fig. 4 is a vertical section taken on line 4—4 of Fig. 2.

Fig. 4^a is a detail of the cam for rocking 65 the cut-off cam lever.

Fig. 5 is a side elevational view partly in section, showing the cam action and the button feed.

Fig. 6 is a section on the line 6—6 of Fig. 70 5, showing the button feed control.

Fig. 7 is a section on the line 7—7 of Fig. 3, showing the plunger and gripping fingers in the resting position.

Fig. 8 is a similar view showing the plunger lowered to receive a button.

Fig. 8^a is a plan view of the top of the plunger.

Fig. 9 is a detail of the wire feed mechanism. 80

Fig. 10 is a detail in perspective of the cut-off cam lever.

Fig. 11 is a detail in perspective of the ejector cam lever.

Fig. 12 is a detail in perspective of the 85 cutting tool.

Fig. 13 is a detail in perspective of the ejector plunger.

Fig. 14 is an elevational view of the button and wire fastening ring. 90

Fig. 15 is a bottom plan view of the wire ring forming die.

Fig. 16 is a section on the line 16—16 of Fig. 15.

This machine is an improvement upon the 95 machine described and claimed in the prior Miner Patent No. 1,140,474 issued May 25, 1915. In this patent a method and apparatus for forming a split wire ring through the eye of the button is described. 100

The machine is adapted to be driven from any source of power, such as an electric motor, or it may be driven from an overhead drive shaft in a way similar to the

driving of most of the existing machines. The shaft *a* may be driven through a suitable clutch mechanism *b*; the said clutch mechanism is arranged to be gripped by 5 the driving member *c* which in turn drives the shaft *a* through one complete revolution.

I reserve the right to claim the clutch and machine control mechanism in my co-pending application Serial No. 634,711, since 10 this clutch arrangement forms no part of the present invention.

It will be sufficient to describe the clutch and tripping mechanism in a general way 15 in this application. The driving shaft *d* is driven directly from an electric motor or by a belt connection to a main driving shaft, and is continuously rotated. (Figs. 3 and 4). The tripping mechanism consists of a 20 stop lever *e* pivoted at *f* to the machine support *g*. The clutch driven member *b* is provided with a projecting tooth *h* which is adapted to be engaged by the stop lever *e*. The shaft *a* has a flanged portion *i* integral 25 therewith and pivoted at *f* is a finger *j* which is adapted to engage with the notch *k* cut in the said flanged portion *i*, for the purpose that will hereinafter appear. The clutch member *b* is counterbored as at *m*; a 30 pin *n* is carried by the clutch and pin *o* is carried by the flanged portion *i* of the shaft while interposed between these two pins is a compression spring *p*.

A lever *q* is pivoted at *r* (Fig. 3) to the 35 machine support, the said lever having pivoted thereto a trip lever *s*, the said trip lever engaging with the stop lever *e* as shown in Fig. 3, so that when a hinged foot lever 110 is depressed the rod *t* which can 40 be attached to the foot lever, will pull down on the lever *q* and thus pull the stop lever *e* away from the tooth *h* that is carried by the clutch member *b*. It is obvious that when this clutch member is released the 45 compression spring *p* will force the clutch driven member in a clockwise direction as indicated by the arrow in Fig. 3, thus causing the rollers *u* of the clutch to ride up on the cam surface *v*, carried by the shaft *a*, 50 until the driving member *c* engages the said rollers and causes the shaft *a* to rotate.

As the tripping lever *s* has been pulled downwardly past the engaging shoulder on the stop lever *e*, the said stop lever *e* is allowed to bear upon the outer clutch surface and to again engage the tooth *h* at the end of the revolution. The machine will therefore stop at one complete revolution even though the rod *t* is held depressed or 60 has been released. The spring *w* attached to the rod *t* and the table *x* causes the rod and lever *q* to return to its initial position when released. In no way can the machine be caused to be overrun one revolution before 65 cause when the stop *e* engages the tooth *h*

at the end of the revolution, the driving member *c* which is continuously running will disengage itself from the rollers *u* due to the momentum of the machine. An instant later the finger *j* will enter the notch *k*. It is seen thus, that the shaft *a* is caused to stop when the lever *e* engages the tooth *h* by stopping the rotation of the clutch roller retaining member *b* (Fig. 3). The shaft *a* will continue to rotate, causing the rollers *u* to fall back on the cam surfaces *v*, thereby disengaging the driving member from the driven member. The advancing of the shaft *a* after the roller retaining member has stopped causes the spring *p* to be compressed and the finger *j* engaging in the notch *k* at the proper time holds the spring under restraint. Also, as the spring *p* bears on the pin *o* carried by the flanged portion *i*, the resulting pressure taken by the finger *j* and the notch *k*, the spring will rotate the roller retaining member *b* in a clockwise movement when the said roller retaining member is released by disengaging the stop lever *e* from the tooth *h* as 90 described.

Keyed to the shaft *a* as at *y* (Fig. 4) are a number of cam discs, 1, 2, 3 and 4; an annular cam groove 5 is provided on the cam 1, and the cam lever 6 for actuating the cutting tool, which has a lug portion 7 that engages in the groove 5, is positively actuated by this cam. A lug 8 is secured to the face of the cam (Fig. 4^a) which causes the cut-off lever 6 to rock, forcing the cutting tool 9 inwardly at the proper time, (Fig. 2).

A cam groove 10 is formed by the cam discs 2 and 3 for guiding the ejector cam lever 11. The cam 4 actuates the yieldable 105 plunger lever which will be more fully described later.

The discs 1, 2, 3 and 4 are riveted together as at 13. The shaft *a* is journaled as at 14 and 15 in the machine support *g*, 110 (Fig. 4). A gear 16 is keyed on said shaft, said gear being adapted to engage with the ordinary counting mechanism which need not be described or shown as it forms no part of the invention. A fly wheel 17 is 115 secured to the end of shaft *a*.

Cam 2 is provided with a circumferential groove 18 around its periphery. This groove is narrower and of less depth for a short distance as at 19, having a cross sectional area substantially the same as the wire 20, which is fed into the ring forming device 21; the cam 2 co-acting with the roller 22, (Fig. 9) will engage the wire by friction and force the same forward to give the correct amount of wire used in forming the wire ring for attaching the button to the fabric. The wire spool 23 is mounted on a bracket 24, secured to support *g* (Fig. 9); a stud bolt 25 on which the spool 23 ro- 120 125 130

tates is carried by the bracket; a spring 26 engaging between the bracket and the washer 27, forces the head 28 of the bolt down upon the spool, tending to retard the 5 free rotation of the spool and to prevent the wire becoming slack. The wire guide member 29 is also supported from the machine support and has a bend 30 therein, which forms additional means for preventing the 10 wire becoming slack. A predetermined length of wire is thus pulled from the spool at every revolution by the restricted portion of the groove 19, and fed into the ring-forming device 21, hereinafter described. 15 The cutting tool 9 cuts off the wire at the proper time, being actuated by the lever 6, already described. As soon as the cut-off plunger has returned to its initial position, the ejector plunger 31 is arranged to be 20 forced downwardly by the cam lever 11 to eject the button and the wire ring (see Fig. 16).

The hollow plunger (Figs. 5, 7 and 8) which receives and supports the button is 25 composed of a sheet metal shell 32, substantially square in cross section. A supporting die 33 is secured to the top of the shell, and the button is adapted to fit in the seat portion 34 of the supporting die 30 33. The plunger is provided with a slot 35 (Fig. 5) extending part of the way down from the top, and the shell 32 is provided near its lower end, with a pin 35^a. The plunger-actuating lever 36 is pivoted 35 at 37 and is provided with a yoke member 38, engaging the pin 35^a to raise or lower the plunger. A cam lever 39 also pivoted at 37 carries a roller 40, which engages the cam 4; the cam lever 39 is provided with a 40 rearwardly extending arm 41 and the plunger-actuating lever 36 is provided with a rearwardly extending arm 42. A bolt 43 secured to the arm 42 extends vertically through a hole 44 in the arm 41 and a take-up spring 45 surrounds the bolt shank bearing against the arms 41 and 42, tending to 45 force the roller 40 against the cam 4. The plunger actuating mechanism is adjustable by the lock nuts 46 threaded onto the end 50 of the bolt 43. This take-up spring acts as a safety device so that if a button is jammed at the head of the plunger the spring will compress as the roller rides on the cam 4 and there is no danger of breaking 55 the plunger or any of the machine parts.

An emergency lever 47 (Fig. 2) is pivoted at 48 to the machine support *g*, and is provided with an inwardly extending pin 49, 60 which is located above the actuating lever 36, (see also Fig. 5) and the plunger may be forced downwardly by pressing the emergency lever 47 down, so that the operator may remove a button that is jammed in the 65 machine.

Now refer to Fig. 7. The machine support *g* is provided with a vertical guide 50, in which the plunger is guided and a cover plate 51 is secured on the face of the support by screws 52, (Fig. 1) to hold the 70 plunger in the guide. The machine support is provided with a pair of slots 52^a (Figs. 7 and 8) on both sides of the guide way and a pair of fingers 53, are each pivoted on a pin 54, and contained within one of the 75 slots 52^a. A spring 55 tends to force these fingers inwardly, inward movement of said fingers being limited by the fact that the said fingers abut the inside face of the slotted portion 52^a, (see Fig. 8) as indicated 80 at 56.

As shown in Fig. 8, the plunger is positioned at its lowest point of travel. The fingers 53 pressing inwardly, provide a gap 57 between the ends of the inwardly extending 85 arms 58 of the fingers 53. The button slides by gravity onto the top of the plunger from the chute 70 (Fig. 5) the head of the button resting in the seat portion 34 of the supporting die 33, and the eye of the button is guided 90 in the space formed by the arms 58. In Fig. 5, the plunger is not in the lowermost position when it is adapted to receive the button from the chute. This locates the correct position of the button and its vertical 95 extending eye, so that the wire ring may be accurately formed through the said eyelet in a way to be described. The cover plate 51 is provided at the top with an inwardly extending plate portion 59 (Fig. 100 5) a slot 60 (Fig. 2) being provided in the upper portion of the said cover plate, and a pair of laterally extending ears 61 (Fig. 7) are carried by the cover plate. A pair of fingers 62 are pivoted on pins 63, carried by 105 the ears 61 and springs 64 are secured to the fingers 62 and cover plate 51, tending to pull fingers 62 downwardly to clamp the button between the inner ends 65 of the fingers 62, and the supporting die 33, as shown in 110 Fig. 7.

Referring again to Fig. 8, it will be seen that the button is received onto the supporting die 33 and centrally located by the seat portion 34, the head of the button lying below the arms 58, of the fingers 53. On upward movement of the plunger the button is carried upwardly, the arms 58 are forced outwardly (Fig. 7) until the arms 58 slip off the button, the springs 55 forcing the arms 58 against the sides of the plunger shell 32. The inner ends 65 of the fingers 62, however, still engage the top of the button as shown in Fig. 7. They continue to clamp the button to its seat on further movement of the plunger upwardly, and the said fingers 62 slip off the edge of the button, a moment before the eye of the button is inserted in the ring-forming device 21, (as shown in Fig. 1). The said fingers 62 are 125 130

arranged to rock in the slot 60, provided in the cover plate 59. When the plunger is withdrawn downwardly the arms 58 of the fingers 53 are forced inwardly over the top of the plunger and take a position as shown in Fig. 8, at which time a button is received onto the head of the plunger, the plunger then rising to a position as shown in Fig. 7, which is the idling position of the machine.

Referring to Figs. 5 and 6, a chute 70 connected to a hopper (not shown) is provided with a longitudinal slot 71 in the top face, and an enlarged central hollow portion 72, the button being guided therein. A control member or selector 73 pivoted to the underside of the chute on the stud 77 is constructed as shown in Fig. 6 to extend over the top of the chute and is provided with downturned ears 74 and 75 which are adapted to intercept the eye of the button. As shown in Figs. 5 and 6, the downturned ears 74 and 75 are arranged to separately intercept the line of buttons. Mounted on the stud shaft 77 is a spring pressed lever 76 which has the downwardly extending arm 78 adapted to engage a cam 79, secured to the side face of the cam disc 4. The cam 79 will force the arms 78 outwardly rocking the lever 76 and forcing the button control member 73 inwardly in the direction of the arrow as shown in Fig. 6. This will cause the downturned ear 74 to assume the position as shown in dotted lines of Fig. 6, releasing the button so that it may slide down the chute; but when the downturned ear 74 is pushed out of the way, the downturned ear 75 is positioned so as to intercept the string of buttons to prevent more than one button sliding down the chute. On the return of the control member 73 to its initial position, the downturned ear 75 is moved to a non-interfering position, but the ear 74 is positioned in an interfering position, which allows the string of buttons to slide downwardly only a short distance or until the ear 74 again intercepts the string as has been described.

Secured to the inner end of the chute 70 are a pair of plates 80, which are what I term an injector. The end of each plate 80 is beveled as at 81, so that if a button does not slide squarely onto the supporting die 33, it will be caused to do so on the initial upward movement of the plunger because of the fact that the edge of the button will be caused to engage this beveled surface 81, and this forces the button onto the supporting die.

The apparatus and method of actually securing the button onto the fabric by means of the wire ring engaging through the button eye forms no part of the present invention, but it is thought advisable to briefly describe this operation.

The ring-forming device 21 (Fig. 16) is provided with a vertical hole 88 therethrough in which the bushing 89 is fitted. The ring-forming die 91 is fitted within this bushing. The wire is fed through a hole 90 (Fig. 15) in the head and the hole 100 in the bushing, said hole 100 being in alignment with the hole 90. The bushing and die are secured to the head by means of a pin 101, (Fig. 16). The eye of the button is forced into the slot 92 and the wire is pushed and caused to travel twice around the spiral groove 93, cut in the die and at the proper time it will be cut off by the cutting tool 9, which is properly timed by the cam 1.

The flattened wings 94 of the ejector 31 are slideable in the slot 95 in the stitching die, and after the wire ring has been cut the ejector is forced downward by the cam groove 10 and lever 11, to eject the ring and button from the ring forming head.

In the operation of the machine the operator presses on the foot lever 110, the rod ^t being pulled downwardly, which actuates the tripping mechanism. This causes the machine to complete one operation. The button already has its eye inserted through the button hole of the fabric, by the operator. The plunger when in its highest position causes the button to enter the head 21, so that the wire that is also fed into the said head, will be caused to coil through the said eye. The cutting tool is actuated to cut the wire ring at the proper time and then the ejector is actuated immediately after the withdrawal of the cutting tool and plunger, so that the eye of the button and the wire ring will be ejected from the ring-forming device, and the fabric can then be moved over by hand in readiness for attaching another button.

In the operation of this machine, there is no danger of the operator failing to pass the eye of the button through the button hole of the fabric, as in the idling position of the machine, the button is positioned as shown in Fig. 7, on a level with the top of the inwardly extending portion 59 of the cover plate 51, which I term the work table. The eye of the button will extend slightly above the work table, and the fabric may be very easily placed over the button and the button hole located around the eye of the button. When the button hole is not positioned directly over the eye of the button, the said eye would tend to pierce the fabric when the ring-forming is in progress, resulting in defective workmanship. This is undesirable because it causes the garment on which the buttons are attached to be declared a "second."

In my machine, when the button hole is not positioned directly over the eye of the button the safety device as described functions and allows the spring 45 to compress

and relieves the tension from the plunger 32, and as a result, the eye of the button does not pierce the fabric.

What I claim is:

5 1. In a button attaching machine, the combination of a member for supporting the fabric, means for supporting a button substantially at the level of the fabric when the machine is at rest, means for lifting the 10 button when the machine is in operation and for momentarily stopping the same in such raised position, and means for securing a fastening device to the button after it is put through the fabric and is lifted, substantially as described.

2. In a button attaching machine, the combination of a member for supporting the fabric, means for supporting a button when the machine is at rest substantially level 20 with the fabric, said means dropping below the level of the fabric to receive the button and rising above the level of the fabric and momentarily stopping in such raised position when the fastening device is secured to the button, and means for applying a fastening device to the button when the same is raised above the level of the fabric, substantially as described.

3. In a button attaching machine, the combination of a table for supporting a fabric, a button feeding chute, discharging at a position below the table, a securing-device forming member above the table, and means for taking the button from the discharge end of 30 the chute below the table presenting the button when the machine is idle at the level of the table and lifting the button to the securing device forming member when the machine is started.

40 4. In a button attaching machine, the combination of a table for supporting the fabric, a securing device forming means supported above the table, a button feeding chute discharging below the table and a plunger for receiving the button from the feed chute below the table presenting the button at the level of the table when the machine is idle and raising the button into the securing device forming means when the machine begins operation.

5. In a button attaching machine, the combination of a table for supporting the fabric, a button feeding chute discharging below the table, a ring forming means including a die located above the table, a vertically reciprocating plunger provided with a button receiving seat, and means for operating the plunger so that it receives the button from the chute below the table presents the button at the level of the table in idling position of the machine and raises the button into the ring forming mechanism when the machine begins to operate.

6. In a button attaching machine, a table 60 for receiving the fabric, a securing device

forming member above the table, means for raising the button and the fabric above the table so the shank of the button enters the securing device forming means, and means for clamping the button onto said raising means during said raising operation.

7. In a button attaching machine, the combination of a table for receiving the fabric, a plunger for raising the fabric and button from the table, means for forming a securing 75 device on said button when in such raised position, and fingers for clamping the button during such raising operation.

8. In a button attaching machine, the combination of a fabric supporting table, a plunger for taking the button from below the table raising it to the level of the table in the idling position of the machine and then lifting it above the table when the machine begins to operate, fingers for guiding the shank of the button onto the end of the plunger when in its lowermost position, and another set of fingers for holding the button in its proper position on the end of the plunger during the raising operations.

9. In a button attaching machine, the combination of a table, a supporting member below the table, a plunger guided in said supporting member for taking the button from a position below the table and raising it above the table, one or more fingers for positioning the button shank properly on the end of the plunger when the plunger is in its lowermost position, and one or more fingers for clamping the button onto the end of the plunger, the said fingers being pivoted to the said support.

10. In a button attaching machine, the combination of a fabric supporting table, a ring forming device supported above the table, a support below the table, a plunger guided in said support and reciprocating vertically through said table, a button feeding chute discharging below said table, said plunger operating to take a button from the end of the chute lifting it to the level of the table and then lifting it above the level of the table into the ring-forming device, a pair of spring controlled fingers pivoted to the support for properly positioning the button on the end of the plunger when discharged from the chute, and a pair of fingers for holding the button to the end of the plunger when being raised, said fingers pivoted supported on the support.

11. In a button attaching machine, the combination of a button feeding chute, a plunger provided with a button seat reciprocating across the mouth of said chute and an injector device located at the mouth of said chute operating in connection with the movement of said plunger to position the button on the end of the plunger when same does not slide into such position when discharged from the mouth of the chute.

12. In a button attaching machine, the combination of an inclined button feeding chute, a plunger reciprocating vertically across the mouth of said chute and provided with a button receiving seat and a block having an inclined surface 81 located at the end of the inclined chute, said inclined surface arranged to engage the edge of the button when lifted by the plunger so as to properly position it on the button receiving seat if this has not been done initially. 40
13. In a button attaching machine, a button feeding member, a plunger for taking the button from the feeding member and lifting the same, automatically, yielding means for actuating the plunger and manually controlled means for operating the plunger in case this is necessary to return the plunger from a "stuck" position. 45
14. In a button attaching machine, the combination of a button discharging chute, a securing device forming means, a plunger for taking a button from the chute and delivering it upwardly into the securing device forming means, yielding means for automatically actuating the plunger in this lifting operation and a manually controlled means for disengaging the plunger in case it becomes stuck. 50
15. In a button attaching machine, the combination of a button discharging means, a securing-device forming means, a plunger for taking a button from the button discharging means and lifting it into the se- 55
- curing device forming means, means for automatically actuating the plunger including a yieldable connection which yields under unusual strain, and manually controlled means for releasing the plunger when the same jams. 60
16. In a button attaching machine, the combination of a member for feeding buttons, a securing device forming means, a plunger for lifting the buttons from the feeding means to the securing device forming means, automatic means including a yieldable connection for actuating the plunger, said yieldable connection yielding under unusual strain, and an emergency lever for returning said plunger to its initial position when the same jams. 65
17. In a button attaching machine, the combination of a button feeding chute, a ring-forming device located above the discharging end of the chute, a plunger for lifting the button from the discharging end of the chute into the ring-forming means, an automatic operator for the plunger including a pair of rocking levers connected in driving engagement by a spring that yields under unusual strain, and an emergency lever which can be engaged with one of the first mentioned levers to release the plunger when the same jams. 70

In testimony whereof he has affixed his 65 signature.

FREDERICK N. ROSS.
